(57) **CLAIM**

The ornamental design for a barbecue grill shaped like Texas, as shown and described.

DESCRIPTION

FIG. 1 is a front perspective view of a barbecue grill shaped like Texas showing my new design;

FIG. 2 is a rear perspective view thereof;

FIG. 3 is a front elevational view thereof;

FIG. 4 is a rear elevational view thereof;

FIG. 5 is a side elevational view thereof, the opposite side being a mirror image;

FIG. 6 is a top plan view thereof;

FIG. 7 is a bottom plan view thereof; and,

FIG. 8 is a sectional view taken along line 8—8 in FIG. 3.

The details shown in broken lines in all views are for illustrative purposes only and form no part of the claimed design.
